Inventor:

Edmund B. Rupard
By Walter M. Fuller Atty

UNITED STATES PATENT OFFICE.

EDMOND B. RUPARD, OF ATLANTA, GEORGIA, ASSIGNOR TO ARMOUR FERTILIZER WORKS, OF CHICAGO, ILLINOIS, A CORPORATION OF NEW JERSEY.

NITER OVEN.

Application filed June 2, 1927. Serial No. 195,906.

In the manufacture of sulfuric acid, the customary practice for introducing niter into the chambers, when nitrate of soda and sulfuric acid are employed to form oxides 5 of nitrogen, is to put the nitrate of soda, together with liquid sulfuric acid, into a cast-iron pot which is exposed to the heat from the burners in a chamber offset from, but in more or less direct communication with, 10 the flues, the heat causing a reaction which boils out the nitric acid formed, the latter passing into the gas flue to the Glover tower and chambers.

The improved niter-oven of this patent 15 does not change this general form of operation, but improves the method in that more heat can be used, thereby causing a quicker and more thorough generation of nitric acid, and also returning more of the sulfuric 20 acid to the chambers.

The new oven avoids or obviates the cost of the cast-iron pots, and, being much more durable, eliminates the frequent occasions for changing the pots, which unavoidably 25 disturbs or upsets the system and makes necessary an excessive nitrate of soda supply, as well as causing the loss in yield which ensues from the temporary derangement of the system.

30 Furthermore, another advantage of the new oven is that it precludes the possibility of running molten niter-cake into the combustion chambers, because there is no trap beneath the pot to be neglected and the 35 safety overflow will drain the niter cake before it reaches a dangerous level.

The novel and improved oven may be built entirely of chemical brick, bonded with acid-proof mortar, heavy linings and all 40 brick layers being laid so that all joints will be broken.

A cast-iron pan may be encased in such brickwork as an extra precaution, if desired, but its use is not at all essential, and, 45 if preferred, the vessel or receptacle, instead of being made or composed of a plurality of associated bricks properly bound or bonded together, as specified, may be formed as a single, complete, ceramic body of the proper 50 size and required shape.

The opening-connecting such vessel to the combustion chamber is made very large, or, in fact, it may be directly located in the flue, so that it, and its contents, will be subjected to ample heat, in fact, greater than 55

has heretofore been customary or possible, and, indeed, the parts may be so arranged that the flames sweep directly over the nitrate of soda and acid mixture.

Other advantages accruing from the use 60 of the novel construction will become apparent to those skilled in this art from a study of the present preferred embodiment of the invention described in detail below and illustrated in the accompanying draw- 65 ing forming a part of this specification.

In this drawing,—

Fig. 1 is a vertical section showing the offset compartment including the niter-oven, this view being a section on line 1—1 of 70 Fig. 2; and

Fig. 2 is a vertical section, on an enlarged scale, on line 2—2 of Fig. 1.

Referring to these views of the drawing, it will be perceived that the construction 75 includes the usual combustion flue 11, which connects, through a passage 12 of substantial size, with the niter-oven proper, comprising a compartment 13 having an open-top vessel or receptacle 14 in its base adapted 80 to accommodate the nitrate of soda and sulfuric acid which may be introduced thereto through the valved charging funnel 15 extended through the top wall of the oven.

This vessel 14 may be formed of chemical bricks enclosing a safety pan 16, or the pan may be omitted, or the structure may be made as a single ceramic unit.

In view of the relatively-large conduit 12, 90 the heat and possibly the flames in the flue 11 find ready access to the vessel and its contents, and, because of the heat-resisting and refractory nature of the vessel, the conduit 12 may be made considerably larger in cross-section than has heretofore been customary, thus subjecting the vessel and its contents to more intense heat, with resulting economical advantages, by reason of a more efficient chemical reaction.

Slightly below the level of the floor or bottom wall of the conduit 12, the vessel 14 has a safety overflow passage 17 through the wall of the oven, its outer end being closed by a gravity-actuated flap valve 18, 105 which will automatically open outwardly to permit a discharge, and will fall closed when no such delivery occurs.

In the old constructions, using the heavy cast-iron pot above a safety iron-pan, the 110

latter has been provided as a trap to catch any of the material which may boil over out of the pot, but if, through neglect, as not infrequently happens, such pan becomes 5 full, the molten niter-cake will flow out into the combustion chambers, and possibly more or less close the connecting passage between the oven and the chambers, to the serious detriment of the proper and efficient operation of the appliance.

All of this danger is avoided by the valved safety overflow, which will drain the liquid niter-cake before it reaches a dangerous level.

15 Inasmuch as the valve or cover-plate 18 normally closes or seals the overflow, the niter-cake will not harden or freeze, but will readily flow out through such passage and automatically open the cap or valve until the excess is relieved, whereupon the valve will close without attention.

In some cases the conduit 12 may be made so large and the other parts of the construction so arranged that the niter-oven

may practically constitute a part of the 25 main combustion flue.

Several changes may be incorporated in the novel and improved oven as presented without departure from the principles of the invention, defined in the appended claim, 30 and without the loss or sacrifice of any of its material benefits and advantages.

I claim:

A niter-oven for use in the manufacture of sulfuric acid, comprising an oven compartment connected by a conduit to the combustion flue of the system and having in its lower part a refractory vessel below said conduit adapted to contain nitrate of soda and sulfuric acid, said vessel having a safety 40 overflow passage through the wall of the oven at a level below said conduit with an automatically outwardly-opening valve normally closing the outer end of such passage.

In witness whereof I have hereunto set my hand and seal.

EDMOND B. RUPARD.
